(57) **CLAIM**

The ornamental design for a pet toy as shown and described.

DESCRIPTION

FIG. 1 is a top, front, left perspective view of a pet toy of my new design;

FIG. 2 is a bottom, rear, right side perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is a perspective reference view of the pet toy of FIG. 1 with feather as an environment element employed in the pet toy; and,

FIG. 10 is a perspective reference view of the pet toy of FIG. 9 with a blanket as another environment element employed to cover part of the pet toy.

The broken lines in the drawings depict portions of the pet toy that form no part of the claimed design.

1 Claim, 10 Drawing Sheets
